UNITED STATES PATENT OFFICE.

ELLIS W. COOPER, OF BLOOMFIELD, NEW JERSEY, ASSIGNOR TO R. HOE AND CO., OF NEW YORK, N. Y., A CORPORATION OF NEW YORK.

FOLDING AND DELIVERING MECHANISM.

1,133,365.

Specification of Letters Patent. Patented Mar. 30, 1915.

Application filed July 29, 1913. Serial No. 781,774.

To all whom it may concern:

Be it known that I, ELLIS W. COOPER, a citizen of the United States, residing at Bloomfield, county of Essex, and State of New Jersey, have invented certain new and useful Improvements in Folding and Delivery Mechanism, fully described and represented in the following specification and the accompanying drawings, forming a part 10 of the same.

This invention relates to certain improvements in folding mechanisms, and has for its especial object the production of a simple and compact mechanism for folding printed or other sheets with a cross-fold and delivering the folded product, the arrangement of the folding and delivery mechanisms being such that the head of the folded sheet is positively taken by the delivery mechanism before the tail of the sheet is released from the folding devices, whereby the sheets may be accurately and rapidly handled and positively controlled during their passage from the folding mechanism 25 through the delivery.

One embodiment of the invention is shown in the accompanying drawings, in which—

Figure 1 is a side elevation, partly in section, with certain parts broken away, of the improved folding and delivery mechanism; and Fig. 2 is an end elevation, partly in section, with certain parts broken away, taken on line 2—2, Fig. 1, looking in the direction of the arrow.

Referring now to these drawings, while the invention may be used in other relations, the machine selected to illustrate it shows the invention in conjunction with the delivery end of a printing machine employing a delivery cylinder, which cylinder is indicated by the numeral 1, and which is driven in any suitable manner.

In accordance with the invention, there is provided a folding mechanism so located with reference to the delivery cylinder that sheets folded by the folding mechanism are positively controlled during their passage through the folder to the cylinder. While the folding mechanism employed may be somewhat varied, in the particular construction illustrated there is a pair of folding rollers 2, 3, located below the delivery cylinder 1 and closely adjacent thereto, so that 55 the head of the folded sheet may be taken by

the delivery cylinder before the tail of the sheet is released by the folding rolls. These folding rolls are mounted in any suitable manner, one of them, as 3, being mounted in adjustable journals so that by adjusting 60 the journals the width of the opening between the rolls may be varied. Preferably, moreover, these adjustable journals of the roll 3 are spring pressed for holding the folding rolls in close folding contact, this 65 construction being usually employed for this purpose.

The sheet S is delivered from the printing mechanism, when the invention is employed in connection with a printing machine, to the folding rolls by means of the usual tapes 4 and is stopped in proper relation with the folding rolls by sheet stops 5. Coöoperating with the folding rolls in the particular construction illustrated is a 75 tucker blade 6 which is operated to tuck the sheet between the rolls in any suitable manner, the tucker blade, as shown, being carried on an arm 7 mounted on a rock shaft 8 suitably journaled in the frame of the machine. This rock shaft is rocked to operate the tucker blade through a rock arm 9 on the shaft 8, having at its free end a stud 10 to which is secured a crank arm 11, this crank arm, at its other end, being carried 80 on an eccentric stud 12 fast on the delivery cylinder 1, by which the crank arm is operated.

The delivery cylinder, when the delivery device is a cylinder, is provided with sheet 90 taking devices which, in the particular construction illustrated, are or may be gripper fingers 13. These grippers may be mounted on the cylinder in any suitable manner. As illustrated, they are secured to 95 a block 14 which is secured to a rock shaft 15 journaled in the cylinder 1. These grippers are operated to open and close to grip a sheet in any suitable manner. As shown, the rock shaft 15, before referred to, has secured thereto a cam lever 16. This lever at one end has secured thereto a cam roll 17 which runs on a cam 18 suitably fastened to the frame of the machine. The grippers are operated to move to open or sheet taking 100 position by the cam, and are closed when the cam roll runs off the high point of the cam by means of a spring rod construction 19 on the other end of the lever 14, before referred to.

To enable the head of the folded sheet to be taken by the sheet taking devices on the cylinder before the tail of the sheet is released by the folding rolls, these rolls are as 5 before stated located closely adjacent the delivery cylinder, this construction also having the advantage of being very compact and taking up little space. In the best constructions, these rolls are located so closely adjacent to the delivery cylinder that the sheet taking devices thereon operate to take the sheet directly from the rolls just after it has been given its fold by the rolls. When 10 this construction is employed, means may be provided for permitting the grippers to so take the sheet without interference from the rolls. While this construction may be somewhat varied, in the particular construction illustrated this is effected by providing one 15 of the folding rolls, as 2, with clearances 20, in which the grippers may enter to pass under the head of the folded sheet and seize the same.

In the best constructions employing folding rolls, sheet guides 21 are provided to cause the sheet to be directed or guided to the grippers after it has been given its fold. From the delivery cylinder the sheets are or 25 may be delivered to any convenient place, 30 as, for instance, an ordinary delivery table 25. Strippers 26 may be provided for stripping the sheets from the cylinder.

While the invention has been shown and described as used in conjunction with a printing machine, it will be understood that 35 it may be used in other relations. It is further understood that it is not to be restricted to the precise arrangement and details of construction shown and described, but that 40 changes and variations may be made in the same without departing therefrom.

What is claimed is:—

1. In a folding mechanism, the combination with a pair of folding rolls, of a delivery cylinder to which the folding rolls deliver the folded product direct, said cylinder being provided with sheet taking devices 45 and so arranged with relation to the folding

rolls that the head of the folded sheet is taken by the sheet taking devices before the 50 tail of the sheet has been released by the folding means.

2. In a folding mechanism, the combination with a delivery cylinder provided with sheet taking devices, of a pair of folding 55 rolls located closely adjacent said delivery cylinder, one of said folding rolls being provided with recesses in which the sheet taking devices of the cylinder may enter to seize the head of the sheet while the tail of the 60 sheet is held by the rolls.

3. In a folding mechanism, the combination with sheet forwarding means, of a delivery cylinder having sheet taking grippers, 65 of a pair of folding rolls located closely adjacent to the cylinder, one of said rolls being provided with recesses in which the grippers may enter to seize the head of a folded sheet, and a guide for directing the head of the sheet to the sheet taking devices. 70

4. In a folding mechanism, the combination with a delivery mechanism provided with sheet-taking devices, of a pair of folding rolls located closely adjacent said delivery mechanism, one of said folding rolls being provided with clearances to permit the sheet-taking devices of the delivery mechanism to enter and seize the head of the sheet 75 while the sheet is held by the rolls.

5. In a folding mechanism, the combination with a delivery mechanism provided with sheet-taking devices, of a folding mechanism located closely adjacent said delivery mechanism, said folding mechanism being provided with clearances into which the 85 sheet-taking devices of the delivery mechanism may enter to seize the head of the sheet while the sheet is held in the folding mechanism.

In testimony whereof, I have hereunto set 90 my hand, in the presence of two subscribing witnesses.

ELLIS W. COOPER.
